BATTERY TERMINAL CONNECTOR

William S. Thomas, Montoursville, Pa., assignor of nineteen per cent to Joseph G. Saricks, 2nd, Freeland, Pa.; nineteen per cent to Herbert T. Flook, nineteen per cent to Stanford Flook, nineteen per cent to Hughes G. Meaker, all of Mansfield, Pa., and five per cent to Christian R. Nielsen, Washington, D. C.

Application December 19, 1936, Serial No. 116,813

9 Claims. (Cl. 173—259)

This invention relates to a terminal connection and more particularly to a device of this kind adapted particularly for use with the post of a storage battery, and it consists in the constructions, arrangements and combinations herein described and claimed.

It is the cardinal purpose of the invention to provide a clamp wherein a binding pressure is provided at diametrically opposite points, insuring positive retention of the clamp upon an engaged post.

It is also an object of the invention to provide a novel construction of dual cam means for effecting the actuation of the clamp through a single rotative operation.

It is a further object of the invention to provide a novel construction of bushing for the pivot bolt of the cam, whereby corrosion and sulphation prevents locking or freezing of the bolt.

It is a still further object of the invention to provide a novel construction of clamp in which a portion thereof is caused to grip positively into the body of the battery post.

Additional objects, advantages and features of the invention will be apparent from the following description, considered in conjunction with the accompanying drawings, wherein

Figure 1 is a top plan view of a connector engaged upon a post of a battery.

Figure 2 is a similar view showing the parts in open position.

Figure 3 is a side elevation of the parts as shown in Figure 2.

Figure 4 is a cross section on the line 4—4 of Figure 1.

Figure 5 is a cross section of a modified form of clamp.

Figure 6 is a top plan view of a further modified form of clamp, partly in section.

Figure 7 is a top plan view of the device constructed for use as a positive terminal connection with a battery.

Figure 8 is a plan view of one of the jaw members.

Figure 9 is a similar view of the other jaw member.

Figure 10 is an elevation of the cam assembly shaft.

Figure 11 is an end view of the cam assembly shaft.

Figure 12 is a top plan view of a further form of clamp.

Figure 13 is a cross section of a modified form of jaw.

There is illustrated a battery post 10 or simi-

lar terminal, which as heretofore constructed has a tapered formation in the direction of its length, upon which there is secured a terminal clamp 11.

The clamp 11 comprises two sections in the form of jaws 12—13, identical in construction, arranged in side by side relation, and each includes socket portions 14 into which one end of a cable 15 may be inserted and secured, as by welding or otherwise. It will be apparent that by this manner of connection with the cable, the sections 12—13 may have individual, free movements permitting the sections to readily adjust themselves to a battery terminal.

The sections 12—13 each have formed in their opposed faces a semi-circular tapering recess 16, corresponding to the taper of the battery post, so that the sections will snugly engage the post. An ear 17 is formed integrally with each section, and includes an aperture 18, the apertures being aligned and bushed as at 19. A pivot bolt 20 is rotatably mounted in the bushing and extends transversely of the post, when engaged by the clamp, as may be seen in Figures 1 and 2.

The bushings 19 are preferably formed of fiber or other suitable material, impregnated with a lubricating substance as desired, so as to eliminate locking or freezing through the building up of copper sulphate between the bolt 20 and ears 17.

Upon the exterior surfaces of the sections 12 and 13, at points opposite the recess 16, cam faces 21 are formed, each cam face having a taper in an upward direction, as may be seen in Figures 1 and 2, the taper stopping short adjacent the base of the sections.

The bolt 20 has formed at each end a cam 22, each cam being in the form of an elongated member of a length to extend beyond the vertical axis of the battery post, and each cam has formed upon its under longitudinal edge a tapering face 23. Each cam further has formed as an integral part thereof a hexagonal nut 24 constituting a means for rotating the bolt. The bolt 20, cams 22 and nuts 24 may be formed as an integral assembly either by welding, swaging or forging operation, whichever may be found most expedient.

In use, the assembly clamp is positioned upon the post of a battery, the recesses 16 loosely embracing the post, the cam members 22 being in the position shown in Figure 2. A wrench or a pair of pliers is applied to either of the nuts 24 to rotate the bolt 20 in a direction to cause the cams 22 to move into engagement with the sec-

tions 12—13. Such movement of the cams brings the faces 23 thereof into engagement with respective inclined faces 21 of the sections 12—13. Rotation of the cam assembly is continued until the cams have moved downwardly upon the faces 23 to a point slightly beyond dead center of the bolt. Obviously, this movement of the cams causes the sections 12—13 to move inwardly toward each other, positively gripping the post, and by reason of movement of the cams to a position beyond dead center of the pivot bolt the cams will be held firmly against loosening movements. To release the clamp rotation of the bolt 20 is reversed, allowing the sections to release the post. It should be noted that the cams are of a length extending beyond the vertical axis of the battery post and that the clamping pressure is mainly upon the post at diametrically opposite points, which insures a very positive grip upon the post.

It will be noted that equal distribution of pressure upon the jaws 12—13 prevents distortion of the jaws and insures proper fit thereof upon the battery post.

25 In Figures 5 and 6 I have shown modifications of the structure of the members 12—13, embodying means partly penetrating the battery post under clamping action. In Figure 5 the interior faces of the members 12—13 are provided with a projected 30 annular rib 25, and in Figure 6 a pair of screws, pins or boss 26 are mounted in the members 12—13, projecting a slight distance outwardly of the recess 16, and preferably, are positioned at diametrically opposite points.

35 In either of these forms of the device, upon actuation of the cam to locked position, it will be apparent that the ribs or screws, as the case may be, will be forced into the post which will be possible due to the fact that the metal constituting the post is comparatively soft.

40 While the structure shown and described in Figures 1 to 6 could be admirably used in connection with the positive terminal of a battery, complications might arise in the connection of the positive cable to the jaws of the clamp, and still maintain the necessary free lateral movement of the jaw members. In Figure 7 I have shown a 45 form of clamp especially designed to accommodate the positive cable, and for an understanding of this construction, attention is invited to Figure 7, wherein the jaw member 12' is provided with a 50 socket 27 into which the cable 28 is inserted and secured, as by soldering, welding, or otherwise. The complementary jaw 13' includes a boss 29 55 adapted to register with a pin 30 and when assembled thereon the jaw 13' will have lateral movements with respect to the jaw 12', the pin 30 acting as a support and guide. If desired, the 60 aperture of the boss may be bushed as at 31, and this bushing will be impregnated with lubricant or otherwise treated to prevent sulphation.

65 It will be obvious, of course, that the pin 30 could be formed of fiber, suitably treated, and in such event the bushing 31 could be omitted.

The jaws 12' and 13' will have cam members 22' formed as previously described, and the operation will be as stated, that is to say, when the cam members 22' engage the cam faces of the 70 jaws, the latter will be moved toward each other, gripping the post firmly therebetween.

75 The assembly of the cams upon the pivot bolt may be accomplished in various ways, in order to obtain a unitary movement of the cam assembly, and in Figures 7, 10 and 11, the bolt 20' is shown

as having fluted ends 32 and the diameter of the bolt is slightly greater than the aperture 33 formed through the cams 22'. Thus, the cams 22 will be pressed upon the fluted ends 32, the flutes cutting into the metal of the cams and the ends 5 of the bolt finally upset or peened.

This construction permits ready assembly of the parts and it will be clearly apparent that the cams will be positively keyed to the pivot bolt for unitary movement.

In Figure 12, I have illustrated a structure of clamp in which a single cam functions to lock the clamp upon a post. In this form the jaw 34 is made quite heavy at the point of engagement with the bolt 35 in order to take care of strains and stresses which may occur upon movement of the cam 36 into engagement with the jaw 37. Omission of one of the cam members will of course necessitate the provision of a bolt having a substantial head 38.

20 In Figure 13 I have shown an impregnated fiber insert 39 in the cam face of one of the jaw members, for the purpose of eliminating sulphation between the cam and jaw at their points of contact. The same results may be obtained however, by providing an insert in the face of the cam members rather than the jaw members.

25 While I have shown and described certain preferred forms of my invention, this is by way of illustration only, and I consider as my own, all 30 such modifications as fairly fall within the scope of the appended claims.

I claim:

1. A terminal connection comprising a pair of laterally separable members each of which include a recess for receiving a battery post therebetween, a bolt journaled in the members at one end, a laterally extensible flexible elastic cable member connected to the other ends of the members, and an elongated cam member on each end of the bolt member and movable to a clamping position upon respective members at diametrically opposite sides.

35 2. The structure of claim 1 in which said cam members are of a length extending beyond the vertical axis of the post and movable to a position beyond dead center of the longitudinal axis of the bolt.

40 3. A terminal connection comprising a pair of members each of which include a recess for receiving a battery post therebetween, a bolt journaled in the members at one end, a flexible elastic cable member connected to the other ends of the members, each of said members having a cam face upon their exterior surfaces and positioned at diametrically opposite sides, an elongated cam member fixed on each end of the bolt, each cam having a cam face cooperable with respective cam faces of the members, and an angular head on the ends of the bolt whereby the 45 bolt and cam members may be rotated in unison.

45 4. A terminal connection comprising a pair of jaw members yieldingly connected at one end, an ear on the other end of each jaw member, each ear having an aligned aperture, each jaw having a semi-circular recess for reception of a terminal post, a cam face on the exterior surface of each jaw positioned at diametrically opposite points, a bolt journaled in the aligned apertures of the ears, said bolt having fixed thereto elongated cam 50 members, one cam member being disposed outwardly of each jaw member, an angular head on the ends of the bolt whereby the bolt and cam members may be rotated in unison, to a position in engagement with the sides of the jaws,

and said cam members having cam faces cooperable with the cam faces of the jaws whereby to move said jaws into binding engagement upon a post.

5. A terminal connection comprising a pair of jaw members, each of said jaws having a socket at one end for reception of a flexible elastic cable member, the other end of each jaw member having an aperture, a lubricant-impregnated bushing in each aperture, said bushings being alined and receiving a bolt therethrough, each jaw having a semi-circular recess arranged in opposed relation for receiving a battery post therebetween, a cam face on the exterior surface of each jaw positioned 10 at diametrically opposite points, an elongated cam member on each end of the bolt disposed outwardly of respective jaw members, said cam members having cam faces cooperable with the cams of the jaw members when said cams are moved 15 into engagement therewith, and said cam members being of a length extending beyond the vertical axis of an engaged battery post and movable to a position beyond dead center of the longitudinal axis of the bolt.
- 20 6. In a terminal clamp, a pair of separable jaw members adapted to receive a terminal post therebetween, one of said jaw members having a laterally extended pin, the other of said jaws having an aperture for reception of the pin, and elongated cam members journalled outwardly of the 25

jaws and movable into clamping action with the jaws, said cam members being of a length extending beyond the vertical axis of an engaged battery post.

7. In a terminal clamp, a pair of separable jaw members, each of said jaws having a semi-circular recess for reception of a terminal post, one of said jaw members having a socket at one end for securing of a cable, a laterally extended pin on the jaw member, the other of said jaw members having a bushed aperture receiving the pin, ears on the other ends of the jaw members, each ear having aligned bushed apertures, a bolt journalled in the ears and including a cam member disposed outwardly of each jaw member and 15 of a length complementary to cam faces on the jaw members and means for rotating the cam members in unison.

8. The structure of claim 7, in which the cam faces include impregnated fiber insert portions. 20

9. A terminal connector comprising a pair of laterally separable members each of which include a recess for receiving a battery post therebetween, a bolt journalled in the members at one end, a laterally elastic cable member connected to the other ends of the members, and a cam member on each end of the bolt member movable to a clamping position upon respective members at diametrically opposite sides. 25

WILLIAM S. THOMAS. 30
